US00D775189S

(12) United States Design Patent (10) Patent No.: US D775,189 S
Caldwell (45) Date of Patent: * Dec. 27, 2016

(54) DISPLAY SCREEN OR PORTION THEREOF WITH A GRAPHICAL USER INTERFACE

(71) Applicant: MX Technologies, Inc., Lehi, UT (US)

(72) Inventor: John Ryan Caldwell, Lehi, UT (US)

(73) Assignee: MX TECHNOLOGIES, INC., Lehi, UT (US)

() Term: 15 Years

(21) Appl. No.: 29/553,418

(22) Filed: Feb. 1, 2016
